UNITED STATES PATENT OFFICE.

JOHN F. O'CONNOR, OF CHICAGO, ILLINOIS, ASSIGNOR TO WILLIAM H. MINER, OF CHAZY, NEW YORK.

RAILWAY-CAR SIDE BEARING.

1,290,306.

Specification of Letters Patent.

Patented Jan. 7, 1919.

Application filed July 15, 1916. Serial No. 109,422.

To all whom it may concern:

Be it known that I, JOHN F. O'CONNOR, a citizen of the United States, residing at Chicago, in the county of Cook and State 5 of Illinois, have invented a certain new and useful Improvement in Railway-Car Side Bearings, of which the following is a full, clear, concise, and exact description, reference being had to the accompanying drawings, forming a part of this specification.

This invention relates to improvements in railway car side bearing.

One object of the invention is to provide a simple, relatively cheap roller side bearing 15 for railway cars and so arranged that the roller will be automatically returned to central or normal position after each actuation.

Another and more specific object of the invention is to provide a roller side bearing 20 having a rocker tilted by the roller during the movements of the latter, the rocker returning the roller to normal position under the influence of gravity, when pressure on the roller is removed.

25 In the drawing forming a part of this specification, Figure 1 is an end elevation of a body and truck bolster of a car and showing my improvements in connection therewith. Fig. 2 is an enlarged top plan 30 view of the improved side bearing proper. Fig. 3 is a longitudinal, vertical section taken on the line 3—3 of Fig. 2. And Fig. 4 is a perspective view of the rocker.

In said drawing, 10 denotes the body bolster and 11 the truck bolster which are pivotally connected at their centers in the usual manner. As shown, the body bolster is provided with a striking plate 12 and the truck bolster has applied thereto the improved 40 side bearing designated generally by the reference A.

The improved side bearing A preferably comprises a base member or casting B which is riveted or otherwise suitably secured to 45 the truck bolster, and an anti-friction roller C. The base member B is of substantially box-like form, open at the top, and has outwardly extended bottom flanges 13 through which pass the securing means, and on its 50 interior, the base member is provided with a suitable inserted tread or wear plate on which the roller C operates.

The retaining member or base casting B is provided with side walls 15—15 and end 55 walls 16—16, the latter limiting the move-

ments of the roller, as clearly appears from the dotted lines shown in Fig. 3. It will be noted that the end walls 16 are inwardly inclined as indicated at 17—17 and from between the lower edges of said portions 17 60 and the raised central portion 18 of the base casting, on which is secured the tread plate 14, are formed sockets or bearings 19—19 for the transversely extending rounded edges 20—20 of the rocker designated generally by 65 the reference D. Said rocker D is of substantially rectangular form, as clearly indicated in Fig. 4 and fits around the roller C. The distance between the end walls 21—21 of the rocker D is slightly less than 70 the diameter of the roller C. Hence, as the roller C is moved to one side or the other of its normal position, it will engage one of the end walls 21 of the rocker on the curved portion indicated at 22 and continued movement of the roller will tilt the rocker D about one of its edges 20, as indicated by the dotted lines in Fig. 3. When pressure on the roller C is removed, the rocker D being in an unbalanced condition, will obviously return to normal under the influence of gravity, and in so doing, will force the roller C back to normal position. It is obvious from the construction shown that the rocker D operates the same whether tilted to 75 one side or the other. The outer surfaces 23—23 of the end walls 21 of the rocker D are preferably of such contour as to fit the inner surfaces of the portions 17—17 when the roller has been moved to its fullest extent so that the upper portion of the end walls 16 of the base casting and the end walls 21—21 of the rocker co-operate in limiting the movement of the roller, thus distributing the stresses over a greater area. 80

From the preceding description, it will be seen that I have provided a roller side bearing which may be relatively cheaply manufactured; wherein is employed a roller of comparatively large diameter presenting a 90 wide bearing surface; and wherein the roller is always returned automatically to normal position after each actuation.

I claim:

1. In a roller side bearing, the combination with a retaining member, and a roller bodily movable therein and directly bearing on a portion thereof, of means for returning said roller to normal position after actuation thereof, said means comprising, a rocker 105

- 2 having portions thereof on opposite sides of said roller, the rocker being tilted by the roller during its movements, the rocker returning to normal under the influence of 5 gravity after removal of the pressure from the roller, thereby returning the roller to normal position.
2. In a roller side bearing, the combination with a retaining member, and a roller 10 bodily movable therein, of means for returning said roller to normal position after actuation thereof, said means comprising, a member mounted in said retaining member and adapted to be rocked about either end thereof 15 as a pivot, the roller engaging one end of said member when moved in one direction and the opposite end when moved in the other direction.
3. In a roller side bearing, the combination with a retaining member, and a roller 20 bodily movable therein, of means for returning said roller to normal position after actuation thereof, said means comprising, a rocker within which said roller is mounted, 25 said rocker being adapted to tilt about two of its edges depending upon the direction of movement of the roller.
4. In a roller side bearing, the combination with a base casting of substantially rectangular form, of a rectangular rocker 30 removably mounted within said casting, the rocker being adapted to be oscillated about either end thereof, and a roller mounted on

a portion of the base casting and confined within the said rocker, the roller actuating 35 the rocker to oscillate it about either of said ends.

5. In a roller side bearing, the combination with a base casting having a central tread portion, of a roller mounted on said tread portion, and a hollow, substantially rectangular rocker surrounding the lower portion of said roller, said base casting being provided with a pair of bearings and the rocker having two of its edges rounded to cooperate with said bearings. 45

6. In a roller side bearing, the combination with a hollow base casting having a centrally raised tread portion, of a rocker of substantially rectangular form having its 50 end walls rounded at their lower edges, the base casting being provided with coöperating bearings for said edges to thereby permit the roller to tilt about either end, and a roller mounted on said tread portion and 55 within said rocker, the diameter of the roller being in excess of the distance between the upper portions of the end walls of the rocker.

In witness that I claim the foregoing I 60 have hereunto subscribed my name this 13th day of July 1916.

JOHN F. O'CONNOR.
